UNITED STATES PATENT OFFICE.

CHARLES MESSICK, OF BRENTWOOD, NEW YORK.

DESIGN FOR A COMBINED WATCHCASE AND APPENDAGE.

Application filed February 11, 1922. Serial No. 666. Term of patent 14 years.

To all whom it may concern:

Be it known that I, CHARLES MESSICK, a citizen of the United States, residing at Brentwood, in the county of Suffolk and State of New York, have invented a new, original, and ornamental Design for a Combined Watchcase and Appendage, of which the following is a specification, reference being had to the accompanying drawing, forming part thereof.

The figure is a plan view of a combined watchcase and appendage showing my new design.

I claim:

The ornamental design for a combined watchcase and appendage, as shown.

CHARLES MESSICK.
